STAPLING MACHINE

William Drypolcher, Valley Stream, N. Y., assignor to Lou Obstfeld, Brooklyn, and Abraham I. Obstfeld, New York, N. Y.

Application May 10, 1934, Serial No. 724,917

40 Claims.

(CL 1-49)

This invention relates to improvements in stapling machines and has reference particularly to stapling machines of the plier type, i. e., a stapler especially adapted for office use and capable of being operated by a single movement of the hand to effect the clinching of a staple.

The present invention is a further development of the invention forming the subject of an application for Letters Patent in the United States, filed October 27, 1933, Serial Number 695,473.

In practically all of the successfully operated stapling machines in use today, the staple is clinched by means of a plunger which is driven downwardly against the staple by a blow struck with the palm of one hand. Wherever the attempt has been made to utilize the plier type of stapler and especially in connection with a magazine feed for the staples, considerable leverage has been required in order to effect the proper drive in causing the staples to first pierce the work to be fastened and then to clinch the ends of the staple in its final fastening position.

With the foregoing in mind it is the purpose of this invention to avoid the difficulties in construction and operation heretofore encountered in this type of stapling device, and to construct the latter so that it may contain in its magazine a liberal supply of staples and at the same time utilize the magazine as one of the plier arms and as a carrier for the staple driving plunger and work holder, the other arm or lever being part of a system operating the driving plunger and work holder and being operatively mounted upon the magazine arm. In accordance with this construction, it requires but the simple function of moving the second arm towards the magazine arm to initiate and bring about one complete stapling operation.

I have accomplished the purpose of my invention by means of a stapling device, one embodiment of which is described in the specification, set forth in the appended claims, and illustratively exemplified in the accompanying drawings, in which,

Figure 1 is a side elevational view of the stapler showing the parts at rest;

Figure 2 is a substantially longitudinally sectional view of the device showing the parts in the full operative position of driving a staple;

Figure 3 is a plan elevational view of the device showing the plunger and head in substantially transverse section;

Figure 4 is an enlarged plan view of the device at the forward end of the staple magazine to

prevent the unintentional projection of staples from the magazine;

Figure 5 is a section on the line 5-5 of Fig. 4, and also shows in section the lower end of the staple driver;

Figure 6 is a sectional view of a further modification of the retractor for the staples;

Figure 7 is a plan view of the jaw bracket and anvil;

Figure 8 is a fragmentary sectional view at the forward end of the device, showing a modification;

Figure 9 is a side elevational view showing a modified connection between the plunger and levers;

Figure 10 is a section on the line 10-10 of Fig. 2, with parts removed;

Figure 11 is a fragmentary top plan view of the combined handle and staple magazine, showing the staple pusher locked in retracted position; and

Figure 12 is a fragmentary top plan view of the guide plate at the forward end of the staple magazine.

Referring to the drawings, 10 denotes the magazine holder forming one arm of the device and comprising a substantial length of channel bar 11, the upright side walls of which along their upper free ends are each provided with a bead or groove 12. Mounted within the bar 11 and attached thereto by means of spot welds is a second channel bar 13, the closed side contacting with the bottom of the bar 11 and the upright sides being spaced slightly from the sides of the first bar 11 to form a channel for the staples 14. The upper ends of the sides of the inner bar 13 are turned inwardly towards each other and parallel to the closed side to form flanges 15 upon which the closed ends of the staples 14 may be supported and guided throughout the channel in the magazine. Spaced above the flanges 15, and mounted at its sides in the beads or grooves 12 of the bar 11, is a guide plate 16 which not only serves as the upper wall of the magazine channel, but which is provided with a longitudinal slot 17 throughout its length to accommodate the staple pusher and latch 18. The staple pusher and latch 18 comprises a flat plate 18a slidably mounted in the magazine channel and having its leading end 18b slightly inclined with respect to the transverse axis of the magazine to accommodate the end of a clip of staples 14 which are arranged as described in United States Letters Patent No. 1,811,060 issued June 23, 1931. Spaced from the leading end of the plate 18a is a

transversely disposed slot 18c in which is loosely mounted the restricted portion of a depending arm or stop 19 of the latch proper, the depending arm 19 projecting into and substantially forming a movable wall within the walls of the inner channel bar 13. The latch is an angular member and the angle between the stop 19 and plate is raised into a bead 20 which overhangs the flanges 15 to prevent the latch being removed. The rearward end of the latch plate is turned upwardly to form a finger piece 21 by means of which the latch may be set. Beyond the finger piece the latch projects to form a lip 22 loosely arranged beneath the turned over end of the plate. The finger piece 21 is provided with a lip 23 at one side to engage a notch 24 cut in the wall of the guide 16 so as to enable the latch to be locked against movement toward the feeding end of the magazine to unintentionally project the staples. The stop 19 of the latch 18 receives one end of a rectangular coiled spring 25 housed within the inner bar 13 and abutting at its rear end a stop 26 which is formed by an angle bar mounted in the end of the bars 11 and 13. The tendency of the spring 25 is to expand within the housing and to yieldably urge the staples toward the leading end of the magazine. The staple pusher plate 18a can be moved rearwardly against the pressure of the spring 25 to the retracted position illustrated in Fig. 11 and by a lateral movement of the finger piece 21 permitted by the loose mounting of the arm 19 in the slot 18c the lip 23 is caused to engage the guide plate 16 in the notch 24 thus releasably locking the staple pusher in retracted position.

The leading end or head of the magazine 10 comprises an upright housing 27 formed by a rectangular wall in its upper portion above the magazine and depending side plates 28 embracing the sides of the outer bar 11 at its extreme end. A plunger 29 which reciprocates in the housing 27 drives the staples. The plunger 29 is a rectangular member having a slot 30 in its rear wall to receive a projecting end of a lock spring member 31, the end thereof being projected through an opening 32 in the housing 27 and into the slot 30. The spring 31 is of the flat type which projects substantially parallel with the rear upright wall of the housing 27 and has its attached lower end mounted in a strap 33 stamped out of the wall of the housing.

The front wall of the plunger 29 carries a driver or blade 34 which is set slightly at an angle with respect to the front wall of the housing to coincide with the position of each staple 14 as it takes its position beneath the driver. A tapered filler plate 35 is arranged over the driver 34 to give the proper alignment of the plunger 29 in the housing 27.

The forward end of the guide plate 16 forms a bridge piece 36, which projects across the space directly beneath the plunger 29, and which is provided with an upturned knob or button 37 to act as a center for a powerful coiled spring 38. The spring 38 is housed within the plunger and at its upper end is stopped by a pin 39, which projects through aligned openings in the extreme upper end of the plunger 29 and through corresponding openings in a cap 40 embracing the upper end of the plunger above the housing 27, and which projects beyond the cap at opposite sides to form fulcrum points for one end of a lever system hereinafter described.

As previously stated the lower end of the housing 27 consists of side walls only, so that the lead-

ing end of the magazine 10 is open and it is at this open end that the magazine is both loaded and discharged. As a consequence of the construction just described, the staples 14 are constantly being urged towards the front end of the magazine 10 by the action of the spring 25 and in order to hold or limit this forward movement, to bring each staple directly beneath and in line with the driver 34, the leading end of the inner bar 13 stops short of the front of the housing 27 by the width of one staple so as to allow the driver to pass, and a door or gate 41 is hinged in a bracket 42 on one side of the housing 27 and releasably locked or latched in a bracket 43 on the opposite side of the housing, to close over the end of the magazine 10 and cover the entire space from the lower end of the closed portion of the housing 27 to the bottom of the magazine or outer channel bar 11 and to prevent the staples from being projected beyond the delivery end of the magazine. The hinge connection for the door 41 is provided with a spring 45 which tends to yieldably urge the door to take its closed position.

It should be pointed out at this point in the description that the purpose of the latch construction 18 in the magazine is to prevent the spring 25 from projecting the staples 14 from the magazine at its open end when the door 41 is opened for the purpose of removing a defective staple or reloading. It is necessary for the operator to retract the latch 18, compress the spring 25 and engage the lip 23 in the notch 24, before opening the door.

As a substitute for the latch arrangement to prevent unintended forward movement of the staples when the gate is open or is being opened, or, as an aid to the latch, a retractor or dog 46, consisting of two arms and a cross piece 46a, is pivotally mounted between the walls of the inner bar 13 on a pin 47 carried by and disposed transversely thereof. A spring 48 is coiled about the pin 47 between the arms, and its ends are disposed against the cross piece and a bracket 49 forming an integral part of the inner bar 13 and embracing the dog 46. The spring 48 tends to urge the cross piece, which projects towards the door, upwardly against the under sides of the flanges 15. The free end of the cross piece 46a projects into the path of the driver 34 and supports the foremost staple fed into delivery position by the staple pusher. Thus, when the driver 34 is actuated to drive a staple it engages said staple and forces the latter downwardly together with the free end of the cross piece against the force of the spring 48. The free end of said cross piece moves on the arc of a circle so that near the end of the downward movement thereof it assumes a position inwardly of the driver 34 out of the path of the latter, as illustrated in Fig. 2, releasing the staple for its final motion to clinching position. The succeeding foremost staple is held from forward movement by the upper portion of the driver blade, and as the latter lifts and returns to its initial position the free end of the cross piece 46a follows the end of the blade in its upward movement which finally reaches an elevation above that of the staples, whereupon the foremost staple moves forward and into the path left by the preceding staple but instead of dropping, its closed end rests upon the free end of cross piece 46a and against the inner face of gate 41. Said gate 41 is provided with a forwardly projected wall portion 44 which provides a space for the arcuate motion of the free end of said cross piece. In the embodiment of the invention illustratively exemplified in Figures 75

4 and 5, the free end of the cross piece of the dog 46 projects into the path of the driver 34 and at its midportion the material is built up to form a barb 50, which in rest position engages between the third and fourth adjacent staples of the leading end of the clip. The staples take substantially the position illustrated in Figure 5 and it will be seen that the main pressure exerted by the magazine spring 25 is against the barb 50 so that when the door is opened the most that can happen is that the staples may be forced slowly past the barb which will prevent the danger of allowing the spring 25 to rapidly project the staples with sufficient force to cause danger to the operator or one handling the stapler. In this construction the downward movement of the driver 34 causes the latter to engage the tip of the cross piece of the dog 46 and to move downwardly out of engagement with the staples which normally move forward to bring the outermost staple of the clip into engagement with the face of the driver. Withdrawal of the driver allows the end staple to take its place in readiness for the next stapling operation.

25 In Figure 6 the tip of the cross piece of the dog 46 is turned up to form a lip 51 which replaces the barb and allows the end staple of the clip to stop against it, the lip being depressed with the dog by downward movement of the driver, whereupon the end staple is projected against the latter and into driving position when the driver is retracted. The dog 46 provided with the barb 50 or with the lip 51 constitutes means to releasably resist projecting the staples beyond the end of the magazine but said dog operating in the manner hereinbefore described permits the staples to be fed successively to delivery position into the path of said driver 34 when the latter is actuated to move the cross 46a downwardly 40 against the force of the spring 48.

Referring now to the means used to operate the plunger 29, 52 denotes the other arm of the plier, which arm is virtually the movable one of the two, the other arm being the magazine 10. The lever arm 52 comprises a rounded free end and a yoke shaped pivoted end, the arms 53 thereof loosely embracing the sides of the plunger housing 27 and being pivotally connected to the arms 54 of a U-shaped bracket 55, which in turn 50 embraces the sides of the magazine 10 and is pivotally mounted on a pin 56 carried by a bracket 57 spot welded or otherwise attached to the underside or bottom of the bar 11 at a point just back of the housing 27. The sides of the bracket 55 between its pivotal connections with the lever arm 52 and pin 56 are provided with rearwardly and upwardly inclined arms 58, to the ends of which the ends of parallel links 59 are pivotally connected, the opposite ends of the links being arranged on opposite sides of the upper portion of the housing 27 and being pivotally connected to the lower ends of depending links 60, which have their upper ends pivotally carried upon the ends of the pin 38 projecting beyond the sides of the cap 40 of the plunger 29.

60 Downward movement of the links 59 to depress the plunger 29 through links 60 is effected by means of a link 61 mounted between the links 59 and arms 53 of the lever arm 52 on pins 62 and 63 carried by links 59 and arms 53, respectively. In accordance with the leverage system described above the amount of leverage exerted by the operator to operate the leverage arm 52 is negligible, and in addition it is possible to utilize

the initial arcuate movement in the lower closed end of the bracket 55 to clamp the papers or material to be stapled into position beneath the leading end of the magazine 10 and comprises a channelled upper face, a longitudinally disposed slot 65 in its mid web portion and a stepped up rearwardly projecting lip 66 beyond the pivotal connection 56. The lip is brought 10 into close contact with the under side of the magazine 10 when the stapler is at rest and the arms separated, and this position is yieldably held by means of a spring 67 which consists of a flat strip disposed against the under side of the bar 15 11 and pivotally mounted laterally thereof by a pin 68, the forward end of the spring being bent back upon itself to form a loop which rests in a groove in the under side of the lip 66. Beyond the loop the spring 67 is curved forwardly and 20 then downwardly to form a finger grip 69. Rearwardly of the pin 68, the spring projects along the under face of the magazine and at the rearward end is turned up and forked to engage opposite sides of the end of the bottom of the bar 25 11. In order to facilitate operation of the stapler with one hand, the upper arm 52 is also provided with a rest 70 against which the joint of the hand between thumb and index finger rests while the first finger hooks over and about the grip 30 69. In this manner the hand is allowed to exert pressure against the two arms 10 and 52 at the points where the maximum leverage consistent with the ease of operation may be obtained and said grip 69 and rest 70 obstruct movement of the 35 hand to points of less leverage. In the operation of the device the leverage and link systems are so proportioned as to cause the closed end or jaw of the bracket 55 to first move upwardly 40 at its forward end adjacent the under side of the magazine 10 before the plunger starts on its downward movement. This movement of the jaw or bracket 55 is resiliently opposed by the resistance offered by the spring 67 against the lip 66. When the grip on the handles is released, 45 the tension of spring 67 tends to separate the jaw from the material and staple before the plunger is retracted.

The staple ends, after being driven through the layers of material to be attached, are brought into engagement with an anvil 71 adjustably mounted in the channel upper face or jaw of the bracket 55 and provided with spaced cuts or dies 72 and 73, respectively, to permanently and temporarily clinch the staples at their free ends. The positions of the anvil 71 are set by a winged or set screw 72a at the end of a screw stud 73 which is carried by the anvil and projected through the slot 65. A guide pin 74 with an enlarged flat head depends from the anvil and moves in the slot 65 to correctly hold the anvil in its lateral position for any adjustment.

In operation the loaded stapling machine is taken in one hand which grips the arms 10 and 52 as previously described and the leading end 65 of the magazine arm 10 is moved to position over the papers to be stapled and the jaw and anvil 71 take their positions directly underneath. The two arms are brought together and initially the anvil is raised to clamp the paper in position beneath the staple in the path of the driver 34. Continued movement of the arms causes the plunger 29 to descend and with it the driver, which engages the end staple and forces it downwardly between the door or gate 41 until its ends 75

pierce the layers of material clamped between the under side of the magazine 10 and anvil 11, and are turned by engagement with one of the dies of the latter.

5 Features which are made possible by the present construction are first, that by means of the compound leverage arrangement the arm 52, which is virtually the movable member, is capable of exerting extreme force in the plunger 10 and driver with the very least amount of exertion on the part of the operator. The lower arm 10, in addition to being a suitable grip in connection with the upper arm 52, is the magazine as well. Another point of importance is the fact 15 that greater leverage results in this construction without a corresponding spread between the two arms being necessary. The particular arrangement of the parts of the present invention enables the same to enjoy the advantages of front feed 20 or reload to the magazine, as well as facilities for making a temporary and permanent clinching operation of the staple.

The door or gate, which has heretofore caused some difficulties in manufacture, may be made 25 according to this invention, as illustrated in Figure 8, of less height than in the construction illustrated in Figs. 1 and 2, the upper portion of the door being replaced by a projection 75 which is bent outwardly and downwardly over the path 30 of movement of the upper or closed end of the staples so that when the latter are ejected from the machine, as the door is opened, the staples will be deflected downwardly. The loading of the magazine having the projection 75 would not be 35 impossible because there is sufficient flex in the clip to enable the same to bend about the projection as it is fed into the magazine.

A modification which permits easy and quick access to the interior of the machine is shown 40 in Fig. 9 where the links 60 are cut out at 76 so that they may be engaged or disengaged at the ends of pin 39 to allow assembly or disassembly of the plunger when desired.

Having now described my invention and the 45 manner in which the same operates, what I claim and desire to secure by Letters Patent is:

1. In a stapling machine, the combination of a pair of arms relatively movable toward each other and a lever-and-link mechanism pivotally associated with the arms and operated thereby, the lower arm being a magazine to receive and deliver a clip of staples, means to urge the clip toward the driving end of the arm, and a driver at the end of the lower arm operated by said 50 mechanism and relative movement of the arms toward each other to pick off a single staple and drive it through the material to be engaged, and an anvil carried by a part of said mechanism in the path of the staple beneath the driver to turn the ends.

2. In a stapling machine, a combination of a pair of arms relatively movable toward each other and a lever-and-link mechanism pivotally associated with the arms, the lower arm forming a magazine to receive and deliver staples from the same end, a spring to project the staples, means to prevent the staples from being projected beyond the delivery end of the magazine, a reciprocating plunger operating at the delivery end 65 of the lower arm and having connection with said mechanism to reciprocate with the movement of the arms toward each other, a driving blade carried by the plunger to engage the staple at the end of the magazine and move it downwardly to pierce the material to be attached, and

an anvil beneath the magazine operable by said mechanism to move upwardly in the direction of the magazine before the plunger starts downwardly to drive the staple against the anvil.

3. A stapling machine of the plier type, comprising a pair of arms adapted to be moved together to drive a staple, the lower arm forming a magazine to receive and deliver staples from the same end, a spring to feed the staples into delivery position, means arranged in the magazine to releasably resist feeding the staples beyond the end thereof, the delivery end of the lower arm having a reciprocating plunger with a driving blade to drive the end staple at the delivery end, a bracket attached to the lower arm and having an anvil adjustably supported beneath the driver to clinch the ends of the staple during its downward movement, said bracket having arms extending upwardly of the lower arm and pivotally supporting one end of the other arm of the pair, and a system of links between the arms of the bracket, the plunger, and the second arm of the pair, whereby movement of the pair of arms toward each other will first move the anvil toward the magazine and 15 in line with the staple and then operate the plunger downwardly to drive the staple against the anvil to clinch its ends.

4. A stapling machine, as claimed in claim 1, in which said magazine has a receiving and delivery end for the staples and including a spring operated hinged gate for closing the delivery and receiving end of said magazine.

5. A stapling machine as claimed in claim 1, including a spring operated hinged gate for the delivery and receiving end of the magazine, and means within the magazine and frictionally engaging between the end staples of a clip to oppose continued forward movement of the staples when the gate is open.

6. A stapling machine, as claimed in claim 1, in which the part which carries the anvil is movable and in which a spring is pivotally carried on the under-side of the magazine to resiliently engage and balance said part during movement of the other moving parts to reciprocate the plunger.

7. A stapling machine, as claimed in claim 1, including finger stops carried by the two arms of the pair to position the operator's hand for gripping said arms.

8. A stapling machine, as claimed in claim 1, in which the anvil comprises a plate having two sets of dies, one thereof for temporary clinching and the other for permanent clinching of the ends of the staples.

9. A stapling machine, as claimed in claim 1, including a lever pivoted within the magazine and having a barb to engage between adjacent staples of the clip, and a spring to urge the lever upwardly and the barb into frictional engagement with the staples, the end of the lever projecting into the path of the downward movement of the driver when the latter is actuated to drive a staple.

10. A stapling machine, as claimed in claim 1, in which the part which carries the anvil is slotted longitudinally thereof and the anvil has a stud projecting through said slot, and a thumb screw adjustable over the stud and against the anvil, the latter having spaced sets of dies in its surface to register with the staple.

11. A stapling machine, as claimed in claim 1, in which said clip urging means includes a slide in said magazine and a latch for said slide to en-

gage the magazine and hold the clip urging means in retracted position and the staples free of any tension to feed them toward the driver.

12. A stapling machine, as claimed in claim 1, in which the magazine has a delivering and receiving end for the staples and including a spring operated hinged gate for closing said delivering and receiving end of the magazine, and a projection arranged in advance of the gate to deflect the staples which may unintentionally be ejected from the magazine when the gate is open.

13. In a stapling machine, the combination of a pair of arms and a lever-and-link mechanism pivotally associated with the arms, the lower arm being a magazine to receive and deliver a clip of staples, means to urge the clip toward the driving end of the arm, means to releasably resist projection of the staples beyond the end of the arm, and a driver at the end of the lower arm operated by said mechanism and movement of the arms toward each other to pick off a single staple and drive it through the material to be engaged, and an anvil operated by said mechanism in the path of the staple beneath the driver to turn the ends of the driven staple.

14. In a stapling machine, a combination of a pair of arms and a lever-and-link mechanism pivotally associated with the arms, the lower arm forming a magazine to receive and deliver staples from the same end, a spring to feed the staples, a reciprocating plunger operating at the delivery end of the lower arm and having connection with said mechanism to reciprocate with the movement of the arms toward each other, a driving blade carried by the plunger to engage the foremost staple fed into delivery position and move it downwardly to pierce the material to be attached, and an anvil movably positioned beneath the magazine and operable under the control of said mechanism to move upwardly in the direction of the magazine before the plunger starts downwardly to drive the staple against the anvil.

15. A stapling machine of the plier type, comprising a pair of arms relatively movable toward each other to drive a staple, the lower arm forming a magazine constructed to receive and provided with means to deliver staples at the same end, a spring to feed the staples into delivery position, the delivery end of the lower arm having a reciprocating plunger with a driving blade to drive the foremost staple fed into delivery position, a bracket attached to the lower arm and having an anvil supported beneath the driver to clinch the ends of the staple during its downward movement, said bracket having arms extending upwardly of the lower arm and pivotally supporting one end of the other arm, a system of links between the arms of the bracket, the plunger, and the second arm whereby relative movement of the arms toward each other will first move the anvil toward the magazine and in line with the staple and then operate the plunger downwardly to drive the staple against the anvil to clinch its ends.

16. In a stapling machine, a pair of arms relatively movable toward each other, a bracket pivotally connected to both of said arms, a housing carried by one of said arms, a plunger movable in said housing, a staple driver operated by said plunger, links interconnecting said plunger with said bracket and with the other of said arms, whereby said driver is actuated to drive a staple when said arms are moved relatively toward each other.

17. In a stapling machine, a pair of arms rela-

tively movable toward each other, a bracket pivotally connected to both of said arms, a housing carried by one of said arms, a plunger movable in said housing, a staple driver operated by said plunger, links interconnecting said plunger with said bracket and with the other of said arms, whereby said driver is actuated to drive a staple when said arms are moved relatively toward each other, and an anvil positioned in the path of said driver, said anvil having permanent and temporary staple-clinching dies and movable with relation to the driver for selectively positioning either of said dies for coaction with said driver in clinching a staple.

18. In a stapling machine, a pair of arms relatively movable toward each other, a bracket pivotally connected to both of said arms, a housing carried by one of said arms, a plunger movable in said housing, a staple driver operated by said plunger, links interconnecting said plunger with said bracket and with the other of said arms whereby said driver is actuated to drive a staple when said arms are moved relatively toward each other, and an anvil carried by said bracket and movably positioned below said housing-carrying arm and in the path of said driver, said bracket being operable under the control of said levers to move said anvil toward said housing-carrying arm.

19. In a stapling machine, a pair of arms relatively movable toward each other, a bracket pivotally connected to both of said arms, a housing carried by one of said arms, a plunger movable in said housing, a staple driver operated by said plunger, links interconnecting said plunger with said bracket and with the other of said arms whereby said driver is actuated to drive a staple when said arms are moved relatively toward each other, and an anvil carried by said bracket and movably positioned below said housing-carrying arm and in the path of said driver, said bracket being operable under the control of said levers to move said anvil toward said housing-carrying arm, said anvil having permanent and temporary staple-clinching dies and movably mounted in said bracket for selectively positioning either of said dies for coaction with said driver in clinching a staple.

20. In a stapling machine, a pair of arms relatively movable toward each other, a bracket pivotally connected to both of said arms, a housing carried by one of said arms, a plunger movable in said housing, a staple driver operated by said plunger, links interconnecting said plunger with said bracket and with the other of said arms whereby said driver is actuated to drive a staple when said arms are moved relatively toward each other, and a spring engaging said bracket to resiliently oppose the relative movement of said arms toward each other.

21. In a stapling machine, a pair of arms relatively movable toward each other, a bracket pivotally connected to both of said arms, a housing carried by one of said arms, a plunger movable in said housing, a staple driver operated by said plunger, links interconnecting said plunger with said bracket and with the other of said arms whereby said driver is actuated to drive a staple when said arms are moved relatively toward each other, and a spring in said housing resiliently opposing the movement of said plunger when said arms are moved relatively toward each other.

22. In a stapling machine, a pair of arms relatively movable toward each other, a housing carried by one of said arms, a plunger and a staple

- driver carried thereby movable in said housing, a lever pivotally connected to said arms, a first link pivotally connected to said plunger, a second link pivotally connected at one end to said 5 first link and at its other end to said lever, and a third link pivotally connected to said second link intermediate the ends of the latter and to one of said arms whereby relative movement of said arms toward each other actuates said plunger and the staple driver carried thereby.
23. In a stapling machine, a pair of arms relatively movable toward each other, a housing carried by one of said arms, a plunger and a staple driver carried thereby movable in said housing, 10 a lever pivotally connected to said arms, a first link pivotally connected to said plunger, a second link pivotally connected at one end to said first link and at its other end to said lever, and a third link pivotally connected to said second link intermediate the ends of the latter and to one of said arms whereby relative movement of said arms toward each other actuates said plunger and the staple driver carried thereby, and a jaw carried 15 by said lever and movably positioned adjacent said housing-carrying arm to clamp the material to be stapled between said jaw and said housing-carrying arm.
24. A stapling machine as defined by claim 23, in which said jaw comprises a staple clinching 20 anvil.
25. In a stapling machine, a pair of arms relatively movable toward each other, a housing carried by one of said arms, a plunger and a staple driver carried thereby movable in said housing, 25 a lever pivotally connected to said arms, a first link pivotally connected to said plunger, a second link pivotally connected at one end to said first link at its other end to said lever, and a third link pivotally connected to said second link intermediate the ends of the latter and to one of said arms whereby relative movement of said arms toward each other actuates said plunger and the staple driver carried thereby, and a jaw carried 30 by said lever and movably positioned adjacent said housing-carrying arm to clamp the material to be stapled between said jaw and said housing-carrying arm.
26. In a stapling machine, a pair of arms relatively movable toward each other, a housing carried by one of said arms, a plunger having a staple driver movable in said housing, a lever pivotally connected to said housing-carrying arm and having an anvil supported beneath the driver to clinch the ends of the staple, said lever having 35 upwardly extending arms and pivotally connected to one end of the other of said relatively movable arms, and a system of links between the arms of the lever, the plunger and the second arm, whereby relative movement of said arms toward each other will first move the anvil toward the housing-carrying arm and then operate the plunger downwardly to drive the staple downwardly against the anvil to clinch its ends.
27. In a stapling machine of the plier type, a pair of arms relatively movable toward each other, a staple driver and an anvil movably carried by one of said arms and operable by relative movement of said arms toward each other 40 to approach each other for clinching a staple, a bracket in which said anvil is mounted pivotally connected to both of said arms, and a flat spring secured to said anvil carrying arm and engaging said bracket to resiliently oppose the relative movement of said arms toward each other. 5
28. A stapling machine as defined by claim 27, in which said spring is pivotally mounted on the anvil carrying arm.
29. A stapling machine as defined by claim 27, in which said spring is pivotally mounted on the 10 anvil carrying arm and in which said spring and the anvil carrying arm are provided with inter-engaging portions for releasably restraining the spring against pivotal movement.
30. A stapling machine as defined by claim 27 15 in which the spring is provided with a finger grip for engagement by the operator's hand.
31. In a stapling machine, the combination of a pair of arms relatively movable toward each other and a system of levers pivotally associated 20 with the arms, one of said arms forming a magazine to receive and deliver staples from the same end, a spring to project the staples, means to prevent the staples from being projected beyond the delivery end of the magazine, a reciprocating 25 plunger operating at the delivery end of the magazine and having connection with the system of levers to reciprocate with the movement of the arms toward each other, a driving blade carried by the plunger to engage the staple at the end 30 of the magazine and move it downwardly to pierce the material to be attached, and an anvil in the system of levers beneath the magazine to move upwardly in the direction of the magazine before the plunger starts downwardly to drive the staple 35 against the anvil.
32. In a stapling machine, the combination of a pair of arms relatively movable toward each other and a system of levers pivotally associated with the arms, one of said arms comprising a 40 magazine to receive and deliver a clip of staples at one end thereof, means to urge the clip toward the delivery and receiving end of the magazine, a driver at said end of the magazine operated by the system of levers to pick off a single staple 45 and drive it through the material to be engaged, a gate for the delivery and receiving end of the magazine, means within the magazine and frictionally engaging between the end staples of a clip to oppose continued forward movement of the 50 staples when the gate is opened, and an anvil carried by the system of levers in the path of the staple beneath the driver to turn the ends. 55
33. In a stapling machine, the combination of a pair of arms relatively movable toward each other and a system of levers pivotally associated with the arms, one of said arms comprising a magazine to receive and deliver a clip of staples at one end thereof, means to urge the clip toward the delivery and receiving end of the magazine, 60 a driver at said end of the magazine operated by the system of levers to pick off a single staple and drive it through the material to be engaged, a lever pivoted within the magazine and having a barb to engage between adjacent staples of the 65 clip, a spring to urge the lever upwardly and the barb into frictional engagement with the staples, the end of the lever projecting into the path of the driver when the latter is moved downwardly to drive a staple, and an anvil carried by the system of levers in the path of the staple beneath the driver to turn the ends. 70
34. In a stapling machine, the combination of a pair of arms relatively movable toward each other and a system of levers pivotally associated 75

with the arms, one of said arms comprising a magazine to receive and deliver a clip of staples at one end thereof, means to urge the clip toward the delivery and receiving end of the magazine, 5 a driver at said end of the magazine operated by the system of levers to pick off a single staple and drive it through the material to be engaged, a projection arranged in advance of the gate to deflect the staples which may unintentionally be ejected from the magazine when the gate is 10 opened, and an anvil carried by the system of levers in the path of the staple beneath the driver to turn the ends.

35. In a stapling machine of the plier type, a 15 pair of arms relatively movable toward each other, a staple driver and an anvil movably carried by one of said arms and operable by relative movement of said arms toward each other to approach each other for clinching a staple, a bracket in 20 which said anvil is mounted pivotally connected to both of said arms, and resilient means secured to said anvil carrying arm and engaging said bracket to resiliently oppose the relative movement of said arms toward each other.

25 36. A stapling machine as defined by claim 35, in which said resilient means is pivotally mounted on the anvil carrying arm.

37. In a stapling machine, a pair of arms relatively movable toward each other, a bracket pivotally connected to both of said arms, a housing carried by one of said arms, a plunger movable in said housing, a staple driver operated by said plunger, links detachably interconnecting said plunger with said bracket and with the other of 35 said arms whereby said driver is actuated to drive a staple when said arms are moved relatively toward each other, and a spring in said

housing resiliently opposing the movement of said plunger when said arms are moved relatively toward each other.

38. In a stapling machine, a pair of arms relatively movable toward each other, a housing carried by one of said arms, a plunger and a staple driver carried thereby movable in said housing, a lever pivotally connected to said arms, a first link pivotally and detachably connected to said plunger, a second link pivotally connected at one end 10 to said first link and at its other end to said lever, and a third link pivotally connected to said second link intermediate the ends of the latter and to one of said arms whereby relative movement of said arms toward each other actuates 15 said plunger and the staple driver carried thereby.

39. In a stapling machine, a pair of arms relatively movable toward each other, a housing carried by one of said arms, a plunger movable in 20 said housing, a staple driver operated by said plunger, a pin extending transversely of said plunger, and means detachably connected to said plunger and actuated by the relative movement of said arms toward each other to operate said plunger, said means including links removably 25 engaging said pin.

40. In a stapling machine, a pair of arms relatively movable toward each other, a housing carried by one of said arms, a plunger movable in 30 said housing, a staple driver operated by said plunger, a pin extending transversely of said plunger, and means detachably connected to said plunger and actuated by the relative movement of said arms toward each other to operate said plunger, said means including links having slot- 35 ted ends removably engaging said pin.

WILLIAM DRYPOLCHER.
